PAINT TRAY FOR ROLLER APPLICATORS

George H. Wabnitz, Rochester, N. Y.

Application May 26, 1950, Serial No. 164,429

6 Claims. (Cl. 15—121.2)

1

The present invention relates to trays for supplying paint to a roller-type paint applicator.

Roller-type paint applicators are coming more and more into use, particularly for applying paint to interior walls. They are easy to manipulate and with them a flat surface can be painted more rapidly than with a paint brush.

One drawback of the roller-type applicator heretofore has been the lack of a satisfactory means for putting paint on the applicator itself. Trays are supplied for this purpose, but the conventional type of tray is just a shallow receptacle adapted to contain only a small amount of paint, and has to be refilled repeatedly even for a small paint job. Moreover, when using the conventional type of tray, it is difficult to distribute the paint evenly around the whole circumference of the applicator. To pick up paint on an applicator it is necessary to roll the applicator back and forth several times along the bottom of the tray. This not only is bothersome and irksome, but slows up the painting job. Furthermore, with a conventional tray, especially when the tray has been freshly filled, the paint flows not only onto the periphery of the applicator but around the ends of the applicator. The paint on the ends of the roller is likely to drip which is an annoyance and an inconvenience; and moreover, it gets into the bearings of the roller, clogging the bearings.

A primary object of the present invention is to provide a tray for use in applying paint to a roller-type paint applicator which will permit complete saturation of the roller with paint more rapidly than is possible with any prior type of tray used for this purpose.

Another object of the invention is to provide a tray for use in applying paint to roller-type applicators which is so constructed that the paint can be applied to the applicator without working or rolling the roller in the tray.

A further object of the invention is to provide a tray for applying paint to a roller-type applicator which is so constructed that the paint will not get onto the ends of the roller or into the bearings of the roller.

A still further object of the invention is to provide a tray for applying paint to a roller-type applicator which can carry a much larger supply of paint than any conventional type tray used for the purpose.

Other objects of the invention will be apparent hereinafter from the specification and from the appended claims.

In the drawing:

Fig. 1 is a plan view of a tray built according

2

to one embodiment of this invention, the roller being shown in the tray in dotted lines;

Fig. 2 is a transverse section through the tray;

Fig. 3 is a longitudinal sectional view of the tray and also showing diagrammatically how the tray may be held in use by the painter; and

Fig. 4 is a view similar to Fig. 3, but showing the tray tipped to apply the paint to an applicator.

The tray of this invention may be made of sheet metal, plastic, or any other suitable material. The tray comprises a container 10, a reservoir section 11, and a trough portion 12.

The container is approximately cylindrical in shape and is, in use, closed at both ends. Its front wall, denoted at 15 (Fig. 3), is formed by bending the bottom 14 of the tray around upon itself. There is a space 16 left between the rolled-over portion 15 of the tray and the bottom 14 of the tray, to provide a mouth or port through which paint may flow out of the container 10 into the reservoir 11.

The trough 12 of the tray comprises a base portion 18, which is part of the bottom 14 of the tray, and the two parallel side walls 19. It has a lip 20 at its forward end which acts to retain the paint in the trough. The side walls 19 are bent inwardly toward one another, to form rear walls for the trough portion, and then are bent at right angles again to form the parallel side walls 23 of the reservoir 11. The rear walls of the trough consist of the rounded lower portions 21 and the upstanding portions 22. The rounded lower portions 21 have approximately the same radius of curvature as the applicator with which the tray is to be used.

Between the side walls or wings 23 of the reservoir 11, there is provided an arcuate-shaped baffle 25 which is approximately twice as high as the space 16 which forms the port for the container 10. The baffle 25 extends approximately for only half the extent of the arcuate portions 21 of the rear walls of the trough.

The container 10 is closed at one end by an integral end wall, denoted at 27, this closed end wall 27 being formed as an extension of one side wall 23 of the reservoir. The other end of the container 10 is closed by a removable cap 29. The container 10 may be made large enough to hold a quart, a half gallon, a gallon, or even more paint.

The bottom 14 of the tray forms the bottom of the reservoir 11, but this reservoir, like trough 55 12, is open at its top. It is filled from the con-

3

tainer 10 by paint flowing out of container 10 through slot 16.

For filling, the container 10 is tipped on end, so that the container 10 is at the bottom, and paint is poured into the top of the reservoir 11 between the baffle plate 25 and front wall 15 of the container until the container is filled. The cap 29 is provided simply to permit cleaning out the container 10 at any time after use.

In using the tray, the painter carries it on his forearm A, gripping it in his hand by inserting his fingers through the grip 39 which is welded or otherwise secured to the bottom of the tray.

In operation, the roller R is held close to the baffle plate 25 by its handle H. By means of a slight downward motion of the arm the operator spills paint over the roller, and with a slight drawing motion of the roller over the bottom of the trough the paint is equally distributed over the roller while on the way to the surface of application. When the roller is returned to the tray for another immersion, it is rolled toward the baffle plate, picking up any paint left from the previous dip, and squeezing it into the reservoir. When the roller abuts against the curved rear walls 24 and baffle portion 25, of the trough, the painter tips the tray slightly, as before and as shown in Fig. 4, to allow the paint in the reservoir 11 to spill over the top of the baffle 25 onto the periphery of the roller R. The trough is long enough to permit the roller R to make substantially a complete revolution as it is rolled over the bottom portion 18 of the trough from the lip 23 to the rear walls 24. The paint spilling over the baffle 25, when the tray is tilted, insures complete coverage and complete saturation of the roller in one traverse of the roller over the trough.

The feature of immersing the roller from its top by spilling paint over the top of the roller, allows the paint to go down over the roller giving complete saturation of the material of the roller without working or rolling the roller back and forth in the tray. After one roll of the roller across the bottom of the tray, the roller material is saturated; and the roller 10 may be applied to a wall to paint the wall.

The distance between the walls 23 of the reservoir is always made less than the length of the roller R with which the tray is to be used. Hence, the channel or spillway over the top of the baffle 25 is centered between the ends of the roller so that the ends of the roller are protected from the paint flow, thereby keeping them free from paint, eliminating dripping and clogging of the bearings.

The top of the baffle 25, as already stated, is at approximately half the height of the roller R. The reservoir opening 16 is approximately half the height of the baffle plate 25. This allows the paint to feed out of the container into the reservoir sufficiently to fill the reservoir to practically the top of the baffle. The container, when filled, keeps a supply of paint at this level. The container, being sealed tight, forms a vacuum preventing the paint from running out of the container.

The present invention provides, therefore, a handy, convenient tray for quickly saturating a roller applicator with paint. Moreover, the tray can carry sufficient paint for a whole room without refilling.

With a tray constructed according to the present invention, a roller applicator can be left in the channel formed by the curved portion 24 of the rear walls of the trough and the baffle 25

4

overnight, thoroughly saturated, so long as the trough is covered with a suitable lid. The roller applicator will be in perfect condition for use the next morning.

Obviously the size of the container, and various dimensions of the tray can be altered to suit the size of the applicator or applicators with which the tray is to be used.

The term "paint," as used herein, is employed in a generic sense, and is intended to include lacquers, varnishes and other similar materials, as well as ordinary paints.

While the invention has been described in connection with a particular embodiment thereof, it will be understood that the invention is capable of further modification, and this application is intended to cover any variations, uses, or adaptations of the invention, following, in general, the principles of the invention and including such departures from the present disclosure as come within known or customary practice in the art to which the invention pertains and as may be applied to the essential features hereinbefore set forth and as fall within the scope of the invention or the limits of the appended claims.

Having thus described my invention, what I claim is:

1. A paint tray for use with roller-type paint applicators comprising a receptacle having a smooth, flat, solid bottom wall, side walls, a front wall, and a rear end wall, and a transverse partition intermediate the front and end walls, said transverse partition dividing the receptacle into a trough portion and a reservoir, the inside surface of said bottom wall in the trough portion of said receptacle constituting a surface on which a roller-type applicator is rolled to pick up paint, the height of said partition being greater adjacent the side walls of the receptacle than in its central portion, said central portion constituting a baffle over the top of which paint may be spilled from said reservoir onto the roller applicator when said applicator is abutting against said partition, said front wall being of approximately the same height as the central portion of said partition, said side walls decreasing in height from said partition to said front wall, and said partition wall having a concave arcuately curved front face in the portion of it which is adjacent the bottom of the receptacle to receive the periphery of a roller applicator when said applicator is abutting against said partition wall and a hand grip secured to the outside surface of the bottom wall of the receptacle beneath said bottom wall, whereby the tray may rest on the forearm of a painter and be held by the painter's hand.

2. A paint tray for use with roller-type paint applicators, having a bottom wall, side walls, a front wall, and a transverse partition extending between the side walls intermediate the ends of the side walls, said partition dividing the tray into a trough, which lies forward of the partition, and a reservoir, which lies rearward of the partition, a container mounted at the rear of the tray, the front of which forms the rear wall of the reservoir, said container having a slot in it directly above the bottom of the tray through which paint may flow from the container into the reservoir, the top of said slot being below the minimum height of the partition, whereby paint may be retained behind the partition between the partition and the front of the container.

3. A paint tray for use with roller-type paint applicators, having a bottom wall, side walls, a

front wall, and a transverse partition extending between the side walls intermediate the ends of the side walls, said partition dividing the tray into a trough, which lies forward of the partition, and a reservoir, which lies rearward of the partition, a container mounted at the rear of the tray, the front of which forms the rear wall of the reservoir, said container having a slot in it directly above the bottom of the tray through which paint may flow from the container into the reservoir, the top of said slot being below the minimum height of the partition, whereby paint may be retained behind the partition between the partition and the front of the container, said partition being arcuately curved in the portion of it which is adjacent the bottom of the tray to receive the periphery of a roller applicator.

4. A paint tray for use with roller-type applicators, having a bottom wall, side walls, a front wall, and a transverse partition extending between the side walls intermediate the ends of the side walls, said partition dividing the tray into a trough, which lies forward of the partition, and a reservoir, which lies rearward of the partition, said partition being of greater height adjacent the side walls of the receptacle than in its central portion, said central portion constituting a baffle over the top of which paint may be spilled from the reservoir onto a roller applicator disposed in the trough against the partition, a container mounted at the rear of the tray, the front of which forms the rear wall of the reservoir, said container having a slot in it directly above the bottom of the tray through which paint may flow from the container into the reservoir, the top of said slot being below the top of the central portion of the partition, whereby paint may be retained behind the partition between the partition and the front of the container.

5. A paint tray for use with roller-type applicators, having a bottom wall, side walls, a front wall, and a transverse partition extending between the side walls intermediate the ends of the side walls, said partition dividing the tray into a trough, which lies forward of the partition, and a reservoir, which lies rearward of the partition, said partition being of greater height adjacent the side walls of the receptacle than in its central portion, said central portion constituting a baffle over the top of which paint may be spilled from the reservoir onto a roller applicator disposed in the trough against the partition, and said partition being curved in its

lower portion adjacent the bottom of the tray complementary to the peripheral curvature of a roller applicator to receive the applicator, a container mounted at the rear of the tray, the front of which forms the rear wall of the reservoir, said container having a slot in it directly above the bottom of the tray through which paint may flow from the container into the reservoir, the top of said slot being below the top of the central portion of the partition, whereby paint may be retained behind the partition between the partition and the front of the container.

6. A paint tray for use with roller-type applicators, having a bottom wall, and two side walls, said bottom wall being bent upwardly at its front end to form a front wall for the tray, said bottom wall being reversely rolled upon itself at its rear end with an approximately cylindrical roll, there being a space left between the front of said roll and the opposed face of the bottom wall, said side walls being bent at right angles toward one another intermediate their ends and then being bent rearwardly at right angles again, the first-named bent portions of the side walls constituting parts of the rear wall of a trough, a transverse partition extending between the second-named bent portions of the side walls and constituting the rest of the rear wall of said trough, said transverse partition being of less height than said first-named bent portions of the side walls, one of the side walls extending over the end of the rolled portion of the bottom wall and constituting an end of a container comprising said rolled portion, and a removable cap closing the other end of said rolled portion, the top of said partition being above the space between the front of the rolled portion and the opposed face of the bottom wall, and said partition and the first-named bent portions of the side walls being curved to receive a roller applicator.
